SILK THROWING AND QUILL OR COP FORM-
ING PROCESS AND APPARATUSJoseph P. McHugh, Scranton, Pa., assignor to
General Patents Corp., New York, N. Y., a cor-
poration of New York

Application June 6, 1933, Serial No. 674,568

10 Claims. (Cl. 117—21)

This invention relates to an improved process and apparatus for throwing silk or rayon and for forming cops or quills and is especially well adapted for making silk and rayon crepe cops or quills. While machines have heretofore been devised for doubling and twisting yarn, such as exemplified by the patent to Allen No. 775,550, none of the prior art methods or machines have been adapted for use in quilling silk and rayon, 10 more especially silk crepe.

It is the purpose of the present invention to provide an economical process and apparatus for both throwing silk and forming quills and to provide for forming quills of crepe silk ready for the 15 shuttle which will not snarl in weaving.

It is conventional practice in throwing silk and rayon crepe and forming rayon and silk crepe cops or quills to employ five separate operations which renders the same laborious and expensive.

20 By the instant invention both the silk throwing and cop or quill forming may be directly accomplished in one uninterrupted operation in a single machine.

It is also an object of the invention to provide 25 a method and apparatus for concurrently throwing silk and forming quills or cops whereby the successive strand layers on the cops formed are effectively interlocked in a manner permitting unwinding in the shuttle on weaving without 30 snarling.

A further object of the invention is to provide 35 an improved method and apparatus for forming quills or cops by starting the winding at one end of the quill or cop to be formed and feeding the thread or strand with a traverse which is always less than the desired length of the quill or cop and with a relatively small gain until the other 40 end of the quill or cop to be formed is reached and then rapidly returning the thread or strand 45 to the first end of the quill or cop and repeating the cycle until the cop is completely formed.

It is a further object to provide a novel mount- 45 ing for the skein swifts or reels and to provide other specific improvements in the doubling and winding mechanism.

Other and more detail objects and advantages 50 will become apparent as the description proceeds.

The invention will be described by reference to 55 the accompanying drawings wherein:

Figure 1 is a view in side elevation of a complete quill or cop forming machine unit;

Fig. 2 is a front elevation of the machine 55 shown in Figure 1;

Fig. 3 is a detail view showing a part of the traverse drive mechanism;

Fig. 4 is a view taken at a right angle to Figure 3 showing the traverse control cams;

Fig. 5 is an enlarged detail view of the roller 5 mechanism and quill spindle release rod mount-
ing;

Fig. 6 is a top plan view of the roller mecha-
nism as shown in Figure 5;

Fig. 7 is a fragmentary detail view taken on 10 line 7—7 of Figure 5;

Fig. 8 is a detail of the latching mechanism taken on line 8—8 of Figure 5;

Fig. 9 is a detail view showing the quill mount-
ing and drive; 15

Fig. 10 is an enlarged detail view showing the central skein carrying drum and one skein carry-
ing arm;

Fig. 11 is a fragmentary detail view taken at a 20 right angle to Figure 10.

Referring to Figure 1 there is a base frame 1, on which the entire mechanism is assembled. A motor 2 is centrally carried on the frame 1 and drives a power belt 3. The frame 1 is designed to carry rows of complementary units at each 25 side thereof. These are, however, constructed in duplication. Therefore, only a single left hand unit is shown and will be described. The belt 3 drives pulleys 4 and 4'; shaft 5 extends down from pulley 4' and carries a worm 6 at the lower 30 end thereof which meshes with a worm gear 7 mounted on a shaft 8 carrying a sprocket 9.

A sprocket chain 10 is trained around the drive sprocket 9. The sprocket chain 10 drives the traverse mechanism designated broadly A and 35 also the roller mechanism designated broadly B.

Chain 10 passes about sprockets 11, 12 and 13. Sprocket 11 in turn drives bevel gears 14 and 15, transmitting power to shaft 16 suitably carried by the frame 1. Power is transmitted through shaft 40 16 for controlling the movement of the traverse mechanism A to be later described in detail.

The sprocket 12 drives bevel gears 17 and 18 transmitting power to shaft 19 for driving the 45 roller mechanism B.

The quill spindle 20 carries an enlarged hub 21 normally in driving contact with the belt 3. The spindle 20 is so mounted at its base that it can be swung to and from contact with the drive belt 3 so that the spindle of any unit may be 50 removed from driving engagement with the belt without stopping the machine or disturbing other units.

Coming now to a description of the mountings for the swifts or reels for the skeins, there is 55

rigidly secured to the upper end of the frame 1 a main supporting arm 22. The arm 22 carries at its free end a central hub 23. The hub 23 in turn carries four arms 24, each carrying at its free end a swift or reel 25. Each reel 25 is constructed to receive a skein. The central hub 23 is rotatably carried by the arm 22 so that any swift or reel 25 may be brought within reach of the operator for tying broken strands or replacing skeins. A locking mechanism for holding the hub 23 in any given position of adjustment with respect to the arm 22 is provided and includes the latch detent 26 extending through arm 22 and adapted to be selectively projected into the holes 27 (see Fig. 10) of the hub 23.

The manner of taking off the strands from the individual skeins is such that the hub 23 can be moved to and held in any position of adjustment without interfering with the operation of the machine. The end of the strand from each skein is threaded through a porcelain eye 28 carried by hub 23; each strand then passes transversely of the hub 23 to the single porcelain condensing guide 29 carried by the arm 22' of the next adjacent unit. From the guide 29 the condensed strand designated 30 is passed down to the roller mechanism B. (See Fig. 2.)

Due to the extreme difficulty of providing perfectly balanced reels or swifts and further to the uneven moisture content at different portions of the skeins mounted thereon, it becomes necessary to provide an individual braking mechanism for each swift or reel to insure a uniform tension of the separate strands taken off from the several skeins.

The braking mechanism for each swift or reel is identical and only one will be described. Each swift 25 is provided with a braking surface 31. (See Fig. 10.) A rubber brake shoe 32 is adapted to bear against the surface 31. The shoe 32 is carried by a wire rod 33 pivotally supported on an insulating bracket 34 carried by the swift supporting arm 24. A coil spring 35 is connected to the rod 33 and tensioned to normally urge the shoe 32 against the surface 31. The opposite end of the rod 33 (see Fig. 11) is bent outwardly and passed through a guide loop 36 and terminates in a right angularly bent end 37. Now the porcelain eye 28 is carried by a wire rod 38 pivotally mounted in an insulated bracket 39 carried by the central hub 23. A spring 40 normally urges the rod 38 and porcelain eye 28 inwardly toward the hub 23.

The bent end 37 of brake rod 33 extends just outside the rod 38 carrying the eye 28. The arrangement is such that when a strand is being pulled through the eye 28 under normal tension, the eye 28 is pulled outwardly against the tension of spring 40 and in turn pulls the lower end of rod 33 out by virtue of its bent end 37. This causes rod 33 to have pivotal movement on the bracket 34 against the tension of spring 35 and thus releases the brake shoe 32.

Now, when the swift or reel rotates too fast, due to any unbalanced condition, it tends to cause a slack in the strand and destroys the normal tension. When this happens, the spring 35 immediately applies brake shoe 32 to the swift and slows it down until normal tension of the strand is restored.

At this point, it is well to note that the arm 38 carrying eye 28 is also adapted, when a strand breaks, to be forced by spring 40 against contact member 41 to close a circuit for controlling a

stop mechanism to be hereinafter described in more detail.

Coming now to the roller mechanism B, a main supporting bracket arm 42 is secured to the upper end of the base frame 1 and supports the entire roller mechanism. The shaft 19 passes longitudinally of the arm 42 to drive the roller 43 through bevel gears 44 and 45 (see Figs. 5 and 6). The supporting arm 42 has fixed thereto a right angularly disposed bar 46. At the lower end of bar 46 there is affixed an extension arm 47 in parallelism with the arm 42. Pivotal mounted on the free end of arm 47 is a swinging bar 48. The swinging bar 48 is provided with a bearing 49 for the shaft 50, carrying the roller 43 and the bevel gear 45. The swinging bar 48 is biased away from the bevel gear 44 on shaft 19 by a coil spring 51 surrounding the pivot 52 upon which the bar 48 is journaled.

The swinging bar 48 is normally held in position with the gear 45 in mesh with bevel gear 44 against the tension of spring 51 by a latch bar 53. The latch bar 53 is provided with a slot 54 through which a bolt 55 extends for attaching the latch bar 53 to the swinging bar 48.

Mounted on the upper end of bar 46 (see Fig. 8) is a bracket 56 which carries a casting 57, pivoted at 58 and adapted in normal position to cooperate with a projection 59 on the end of latch bar 53 to hold the swinging bar 48 in position with gears 44 and 45 in mesh. The casting 57 also carries an electromagnet 60 and a pivoted armature 61. The armature 61 pivoted at 62 carries a trigger finger 63 adapted when the magnet 60 is energized to engage a projection 64 carried by the gear 44 on shaft 19.

The arrangement is such that when the electromagnet 60 is energized through the closing of a circuit due to the breaking of a strand, the armature 61 is attracted and causes the trigger 63 to move into the path of a projection 64 on gear 44.

The projection 64 moves the trigger 63 and rocks the casting 57 about the axis 58 to release the latch bar 53. Release of latch bar 53 allows spring 51 to swing the arm 48 to cause disengagement of bevel gears 44 and 45 and allow roller 43 to stop.

Passing now to the means for disconnecting the quill carrying spindle 20 from the driving belt 3, it will be noted that the latch bar 53 is provided at its outer end with an aperture 65 through which extends a spindle releasing rod 66. The rod 66 is pivotally mounted at its lower end on a pivot 67 about which it is moved by the latch arm 53 when swinging arm 48 is released and moved by the spring 51.

As shown in Figure 2, the spindle releasing rod 66 extends behind a finger 68 carried by the mounting 69 for spindle 20. It will be observed that the mounting 69 is journaled upon a vertical pivot 70 which is eccentric to the axis of spindle 20, the vertical pivot 70 being supported by a fixed bracket 71 carried by the frame 1. There is also carried by the bracket 71 a fixed brake shoe 72. (See Figs. 2 and 9.)

The action is as follows: The mounting 69 carrying the spindle 20 is normally urged toward the belt 3 by a coil spring 73 (see Fig. 9) to insure driving engagement between belt 3 and spindle hub 21. Now, when magnet 60 (Fig. 5) causes the release of latch bar 53, the latter, due to the action of spring 51, forces spindle releasing rod 66 outwardly against the finger 68 to swing the spindle mounting 69 about the eccentric pivot 70 and move the spindle hub 21 from

engagement with belt 3 and into engagement with fixed brake shoe 72 to stop the spindle.

Before leaving the spindle releasing rod 66, it will be further observed that when this rod is moved to release spindle hub 21 from driving engagement with belt 3, it also, through the medium of rod 74, opens contacts 75 in series with magnet 60 to deenergize the same. The swinging arm 48 and spindle releasing rod 66 remain in their released position, until manually restored by reengagement of the latch 59 on bar 53 with the pivoted casting 57, to maintain the roller 43 and the spindle 20 inoperative.

Returning to the roller 43, the composite strand 15 30 coming from the porcelain guide eye 29 is drawn through a porcelain eye 76 supported by the latch bar 53 in a position directly above the left hand end of roller 43 as viewed from the front. The bolt 55 carries a porcelain guide 11 20 immediately above the roller 43. The roller 43 which is mounted to rotate with shaft 50 and bevel gear 45, is provided on its circumference with three flat bottomed grooves or channels 78, 79 and 80 separated by square shouldered flanges 25 81.

The thread 30 leaves the eye 76, enters the groove 78 adjacent the left side thereof, is carried once around roller 43 in groove 78, passes thence over porcelain guide 11 into the groove 30 79, once again around the roller 43 in groove 79, thence passing again over porcelain guide 11 to groove 80, thence to porcelain eye 82 and on to the traverse mechanism hereinafter described. The thread is caused to roll axially of the roller 43 in the grooves thereon, whereby the thread delivered to the traverse mechanism is partially twisted. The flat bottomed grooves 78, 79 and 80, together with the square shouldered flanges 81 40 are particularly advantageous in giving a tightly twisted thread and preventing snarling and entangling of the thread upon the roller.

The improved traverse operating and control mechanism by which applicant's novel method of quill forming is accomplished will now be described. Returning to the driven shaft 16, a heart-shaped cam 83 is carried thereby, which oscillates an arm 84 loosely journaled upon a rocker shaft 85 extending parallel to shaft 16.

The arm 84 carries a cam follower roller 86 which rides on cam 83 to cause oscillation of arm 84. The arm 84 also carries a shaft 87 journaled therein on one end of which is fixed a half-heart cam 88 and on the other end there is carried a worm gear 89. The worm gear 89 and half-heart cam 88 are driven from shaft 16 by means of sprocket 90 on shaft 16, chain 91, sprocket 92 mounted on rotating sleeve 93 loosely journaled upon shaft 85. The sleeve 93 carries at its opposite end a worm gear 94 which drives 60 a worm gear 95 upon a shaft 96 extending at right angles to shaft 85 and journaled in a bearing 97 carried by rocker arm 84. The shaft 96 carries at its opposite end a worm 98 which drives gear 89 and half-heart cam 88.

The shaft 85 has affixed thereto a rocker arm 99 which carries at its free end a cam follower roller 100 riding upon the half-heart cam 88. Shaft 85 carries at its outer end a bell-crank lever 101 (see Fig. 2), the horizontal arm of which 70 carries a roller 102 at its free end. The roller 102 engages a thrust plate 103 on the lower end of the traverse reciprocating rod 104 mounted in a guide bearing 105, supported on frame 1 and carrying horizontal ring supporting rods 106 at its upper end. The rods 106 are common to a

plurality of units and carry the ring 107. The vertical arm of bell-crank 101 is pivotally connected to a rod 108 which operates bell-cranks similar to 101 individual to other units and which cooperate to actuate ring supporting rods 106. 5 The ring 107 receives and guides the thread 30 as it is wound to form a cop or quill on the spindle 20.

The operation of the traverse is as follows: The heart cam 83 directly driven by shaft 16 rotates 10 at a relatively rapid speed and produces through arms 84, 99 and 101 traverse movement of uniform amplitude. The amplitude of the uniform traverse is controlled by the size of cam 83 and is intentionally always less than the desired 15 length of quill or cop to be formed. The half-heart cam 88 controls the traverse gain on the quill. Cam 88 moves much slower than cam 83. A ratio of 15 to 1 is found satisfactory, though this may be varied if desired. On each rotation 20 of cam 83 there is but a small movement of cam 88 which translated to the traverse causes it to gain on each rotation of cam 83 proportioned to the movement and pitch of the cam 88.

The cam 88 is so constructed that the cam 25 follower 100 rides during seven-eighths of each revolution thereof on the curved face of the cam and returns to the point of beginning in but one-eighth of a revolution of cam 88. It will thus be observed that after the total gain provided by 30 the curved surface of cam 88 has been effected, there is a quick return to the point of beginning. Due to the form of cam follower 100, the return is effected in much less than one-eighth of a revolution of cam 88. Translated to the quill or 35 cop the winding commences at the bottom, the upward traverse is uniform. The downward traverse is also uniform but always shorter than the upward traverse. When the topmost traverse is reached, the thread is rapidly returned to 40 the bottom of the quill and the cycle repeated.

The cop or quill is built up from the bottom by successive layers of thread, each layer comprising a plurality of overlapping traverses. This results in the formation of a cop or quill having 45 a very effective interlocking wind and one which will unwind in the shuttle on weaving without snarling. This feature of the invention is of great value and I am not to be limited to the precise form of mechanical movement disclosed by 50 which this advantageous result is obtained, since other mechanism than that shown may be employed.

No electrical diagram of the circuit for the electromagnet 60 of the stop mechanism is shown, 55 it being obvious that this circuit is closed upon the breaking of any one of the strands coming from the skeins on reels 25 through the action of the rod 38 carrying the porcelain eye 28 as heretofore described, and that the circuit is broken by the spindle release rod 66 when the stop mechanism has been actuated.

In accordance with the present invention, it is possible to throw silk and form crepe silk or rayon 65 cops or quills in one uninterrupted operation with but one twisting and winding operation. This has never to my knowledge been heretofore accomplished. Crepe silk or rayon requires around sixty-five twists per linear inch and no machine has heretofore been devised for both throwing 70 the silk and giving a cop or quill of thread of this character directly ready for the shuttle of the loom. According to this invention, the quill spindle is driven at a very high speed approximating 15,000 R. P. M. With this permissible speed 75

and the method of twisting and cop forming employed, I am able to turn out crepe silk or rayon quills or cops in one operation, taking the rovings from the skeins and producing finished cops.

5 By the term "lustrous yarn" as employed in the appended claims, I mean to embrace such yarns as raw silk, rayon, or artificial silk, spun silk, spun rayon or yarn made from any of the above fibers, as well as so-called synthetic pigment 10 yarns.

The foregoing description is illustrative only, the invention being limited and restricted only by the scope of the appended claims.

Having thus described my invention, what I 15 claim is:—

1. A multiple down-spinning apparatus for continuously producing in a single spinning step fully thrown lustrous yarn in the form of headless packages ready, without re-drawing, coning, or 20 copping, to directly enter fabric forming machinery, comprising means for supplying a plurality of ends to feed roller means, ring spinners receiving the yarn from the feed roller means, means for correlating the feed roller drive 25 and the revolutions per minute of the packages to impart, in a single spinning step, the required twist necessary to fully throw the yarn, stop motion means for interrupting the formation of any package upon the breaking of a thread supplied 30 thereto, and means for winding the fully thrown yarn directly from the ring spinners on the final packages, said winding means embracing a traverse motion such as will permit interruption and 35 resumption in the formation of any individual package at any point in the formation thereof without in any way affecting the formation of that or any other package produced.

2. A multiple down-spinning apparatus for continuously producing in a single spinning step 40 fully thrown lustrous yarn in the form of headless packages ready, without re-drawing, coning, or copping, to directly enter fabric forming machinery, comprising means for supplying a plurality of ends to feed roller means, said feed roller means 45 being so constructed as to impart uniform tension to the yarn and allow the twist to move back on the yarn to a point well in advance of that where the yarn leaves the roller means, ring spinners receiving the yarn from the feed roller means, 50 means for correlating the feed roller drive and the revolutions per minute of the packages to impart, in a single spinning step, the required twist necessary to fully throw the yarn, stop motion means for interrupting the formation of any 55 package upon the breaking of a thread supplied thereto, and means for winding the fully thrown yarn directly from the ring spinners on the final packages, said winding means embracing a 60 traverse motion such as will permit interruption and resumption in the formation of any individual package at any point in the formation thereof without in any way affecting the formation of that or any other package produced.

3. A continuous method for producing in multiple down-spinning apparatus fully thrown lustrous yarn in the form of headless packages ready to enter fabric forming machinery, comprising drawing the silk directly from skeins, supplying the same to feed roller means, thence supplying 65 the yarn to the traveler of a ring spinner so operated as to impart to the yarn the entire required twist in a single spinning step, then winding the fully thrown yarn on packages ready, without re-drawing, coning, or copping, to enter fabric forming machinery, and effecting the winding of the 70

package through the medium of a traverse motion such that interruption and subsequent resumption of the winding of any package may occur at any point in the formation of any package without in any way affecting the form of the packages 5 produced.

4. A continuous method for producing in multiple down-spinning apparatus fully thrown lustrous yarn in the form of headless packages ready 10 to enter fabric forming machinery, comprising drawing the silk directly from skeins, supplying the same to feed roller means, imparting to the yarn a preliminary twist as it advances over the surface of the feed roller means and before the 15 yarn is subjected to the centrifugal action of spinning, thence supplying the yarn to the traveler of a ring spinner so operated as to impart to the yarn the entire required twist in a single spinning step, then winding the fully thrown yarn on 20 packages ready, without re-drawing, coning, or copping, to enter fabric forming machinery, and effecting the winding of the package through the medium of a traverse motion such that interruption and subsequent resumption of the winding 25 of any package may occur at any point in the formation of any package without in any way affecting the form of the packages produced.

5. An apparatus for producing completely 30 thrown lustrous yarn in the form of headless packages ready to enter fabric forming machinery in one continuous operation employing a single spinning step, comprising means for supporting individual ends in the form of skeins, means for drawing the material from the skeins and supply- 35 ing the same under uniform tension to the traveler of a ring spinner, means intermediate the skeins and the traveler embracing feed roller means adapted to allow the twist in the yarn to move back a substantial distance beyond the 40 point of passage thereof from the feed roller means whereby the yarn, when initially subjected to the centrifugal action of the ring spinner, is possessed of a substantial preliminary twist, stop motion means for interrupting the formation of 45 any given package when there is a break in the thread supplied thereto, means for winding the spun yarn directly from the traveler on a package suitable for use in fabric forming machinery, and means for correlating the feed of the yarn to 50 the ring spinner and the revolutions per minute of the package to secure, in a single spinning step, the requisite twist for the finished yarn, said winding means embodying a traverse motion adapted to build headless packages of uniform 55 contour regardless of interruption in the formation of the package at any stage in the building thereof.

6. In a multiple down-spinning machine, the 60 combination of a plurality of units each embracing means for doubling a plurality of individual strands of lustrous silk, means for feeding the resultant doubled thread to a down-spinner at such a rate as to impart the entire twist required to fully throw the yarn in a single spinning step, 65 means for winding the spun yarn directly on headless packages so formed as to directly enter fabric forming machinery, stop motion means for interrupting the formation of any given package upon breaking any single end supplied thereto, and means associated with said package forming means permitting the resuming of winding of any package at any time during formation thereof without varying the final form of the package, whereby yarn is packaged, ready to en- 75

ter the fabric forming machinery, in a single spinning step.

7. In a multiple down-spinning machine, the combination of a plurality of units each embracing means for doubling a plurality of individual strands of lustrous silk, means for feeding the resultant doubled thread to a down-spinner at such a rate as to impart an initial twist in excess of twenty turns per inch to the yarn in a single spinning step, means for winding the spun yarn directly on headless packages so formed as to directly enter fabric forming machinery, stop motion means for interrupting the formation of any given package upon breaking any single end supplied thereto, and means associated with said package forming means permitting the resumption of winding of any package at any time during formation thereof without varying the final form of the package, whereby yarn is packaged, ready to enter the fabric forming machinery, in a single spinning step.

8. A multiple down-spinning apparatus for producing fully thrown lustrous yarn in the form of headless packages ready without re-drawing, coping or coning, to directly enter fabric forming machinery in one continuous operation employing a single spinning step comprising a plurality of units, each embracing means for supporting individual ends in the form of skeins, means for drawing the ends from the several skeins of each unit and supplying the composite yarn under uniform tension to the travelers on ring spinners, means intermediate the skeins and the travelers for supporting a length of yarn adequate to absorb the twist imparted to the yarn by a single spinning step without creating such tension as would break the yarn under normal operating conditions, vertical spindles for directly receiving the thrown yarn from the travelers of the ring spinners, means regulating the rate of feeding of the yarn to the travelers and the revolutions per minute of the spindles to impart to the yarn in a single spinning step the entire required twist to fully throw the same, stop motion means for interrupting the formation of any given package when there is a break in an end supplied thereto, means for forming packages of predetermined contour on said spindles, said package forming means embodying a traverse motion adapted to build headless packages of uniform contour regardless of interruption in the formation of any package at any stage in the building thereof.

9. A multiple down-spinning apparatus for continuously producing in a single spinning step fully thrown lustrous yarn in the form of headless packages ready without re-drawing, coning or coping, to directly enter fabric forming machinery, comprising a plurality of units, each embracing a vertical spindle, means associated with each unit for supporting a plurality of in-

dividual ends, means for supplying said individual ends to feed roller means, said feed roller means having a sufficient circumferential area to impart uniform tension to the yarn and allow the twist to move back on the yarn to a point well in advance of that where the yarn leaves the feed roller means without thereby causing slippage on the feed roller means, ring spinners receiving a doubled yarn from each feed roller means, means for correlating the speed of the feed roller means and the revolutions per minute of the vertical spindles to impart in a single spinning step the entire required twist to fully throw the yarn, stop motion means for interrupting the formation of any package upon the breaking of any single end supplied thereto, and means for winding the fully thrown yarn directly from the ring spinners on the final packages, said winding means embracing a traverse motion such as will permit interruption and resumption in the formation of any individual package at any point in the formation thereof without in any way affecting the formation of that or any other package produced.

10. A multiple down-spinning apparatus for continuously producing in a single spinning step fully thrown lustrous yarn in the form of headless packages ready, without re-drawing, coning, or coping, to directly enter fabric forming machinery comprising a plurality of individual units each embracing a vertical spindle and means for supporting a plurality of individual ends, means for doubling a plurality of ends and supplying the resultant doubled yarn under uniform tension to the travelers of the ring spinners, said means for doubling and supplying the yarn to the travelers embracing means for maintaining intermediate the individual end supplies and the travelers a sufficient length of the doubled composite yarn to absorb the twist incident to completely throwing the yarn in a single spinning step without thereby placing on the yarn such tension as will under ordinary operating conditions cause breakage of the yarn, means for correlating the rate of supply of the yarn to the travelers of the ring spinners and the revolutions per minute of the vertical spindles to impart in a single spinning step the entire twist necessary to fully throw the yarn, stop motion means for interrupting the formation of any package upon the breaking of any single end supplied thereto, and means for winding the fully thrown yarn directly from the travelers of the ring spinners on the final packages, said winding means embracing a traverse motion such as will permit interruption and resumption in the formation of any individual package at any point in the formation thereof without in any way affecting the formation of that or any other package produced.

60

JOSEPH P. McHUGH.
